COMPOSITE EVAPORATIVE COOLER PADS

William H. Goettl, Phoenix, Ariz.

Application April 19, 1954, Serial No. 424,101

4. Claims. (Cl. 183—13)

This invention pertains to composite evaporating pads for evaporative air coolers.

Heretofore, pads for evaporative coolers have, for the most part, been made of porous fibrous substances, such as, for example excelsior. This substance is comparatively cheap, and efficient but the fibrous structure is so open that in many areas of the pads air is drawn into the cooler without adequate filtering, even when the pad is wet. Further, when the cooler is shut down and the pads allowed to dry, much dirt and dust is accumulated in the fibers which is drawn into the cooler and blown into the area being cooled when the cooler blower is started before the pads are fully wet.

At other times droplets of water are drawn through loose portions of the fibrous material and blown into the room being cooled.

Various means have been tried to overcome these objections. In some instances the excelsior was covered with cotton fabric, such as cheesecloth. But this quickly became covered with dust, dirt, dead insects and the like and interfered with the washing out of these substances that takes place in natural excelsior. It was also found that making the pads thicker than approximately two inches interfered with efficient evaporation of the water passing downward through the pad and increased the resistance of the pad to the flow of air through it. In time the whole pad became fouled and had to be changed.

In view of the foregoing, one of the objects of my invention is to provide an evaporating pad for evaporative type air coolers which has a composite pad consisting of an outer layer of water absorbent fibrous wood excelsior, for efficient evaporation, and an inner layer of non absorbent mineral wool, treated with an oily substance to render it water repellent;

A second object is to provide an evaporating pad for evaporative air coolers consisting of an outer layer of water absorptive fibrous material to evaporate water passing downward over this material, and an inner air filtering layer of finely spun fibrous inorganic substance, such as glass wool, treated with a heavy petroleum oil, to render it water repellent;

A third object contemplates the incorporation of a composite pad, as above described, in a frame adapted to fit into a pad opening in a cooler case, having a water supply trough at the top delivering water to the top of the excelsior pad only, and lattice means for binding the two pads together and for securing the outer fibers of each pad portion in place.

I attain the foregoing objects by means of the structure, substances and combinations of parts illustrated in the accompanying drawings, in which—

Figure 1 is a sectional elevation of a fragment of an evaporative cooler, showing my improved pad in position in one of the pad openings;

Figure 2 is an elevation of the back face of an edge portion of said pad; and

Figure 3 is an elevational view of the front face of an edge portion of said pad.

2

Similar numerals refer to similar parts in the several views.

In the drawings 2 indicates the air cooler case, 3 the blower within the case and 4 the opening in the case side 5 which is closed by evaporating pad 5 in pad frame 6.

It will be noted that the pad frame 6 is closed on the outside by a louvered plate 7 and on the inside by a coarse screen 8. A water distributing trough 10 at the top of the frame 6 receives water from water supply pipe 12 and distributes it to the top of the outside portion 15 of the pad 5 through openings 14 cut through the front side 16 of the trough along its length.

The pad 5 is composite. The front portion 15 is composed of wood excelsior pressed into frame 6 while it is held horizontally. After installation in frame 6 it receives water to be evaporated from trough 10. This water trickles downward through this portion of the pad, being absorbent into the fibers of the excelsior and producing refrigeration as air is drawn inwardly through the pad by blower 3. Excess water drains from the bottom of the pad into the sump 18 in the bottom of the cooler case 2 in the usual manner.

The back portion 20 of the pad 5 is composed of a flat pad of inorganic fibrous material such as matted

25 finely drawn or spun glass fibers, or mineral wool, which is finely drawn fibers of slag folded in random fashion

20 into a mat or pad. This pad, after being spread out on pad part 15, which is positioned horizontally during

30 manufacture, is then treated by spraying with a non

hardening heavy mineral oil, such as heavy thick refined

petroleum. This oil sticks to the inorganic fibers of the

inner pad portion 20 and tends to make this pad portion

25 water repellent. Unevaporated water particles from pad

portion 15 are stopped by this pad portion and trickle

35 down its front face along the area of contact 22 between

the two pad portions. Dust, accumulated on the outer

pad portions, when it is dry is caught by the treated fibers

30 of the inner pad portion 20 and later washed down into

the case sump, when the water flow becomes adequate.

40 If it is desired to run the cooler dry, the inner pad

portion acts as a filler, and when the cooler is not used

for a period of time dirt does not filter into the interior

of the case.

45 From the foregoing it will be understood that the pad

5 is termed composite because it has outer and inner

layers or portions which are of entirely different materials.

The fibrous wood excelsior 15 composing the front

layer of the pad receives water from trough 10 and ab-

50 sorbs a portion of it and provides efficient evaporating

surfaces for the production of refrigeration. The back

portion or layer 20 of the pad acts as a dust and water

filter. Since water is distributed to the front layer, only,

the natural course of the water is downward through this

55 front layer to the sump 18. However, air passing through

the pad may draw droplets of water toward layer 20, but

since the material of this pad portion is water repellent,

no great amount of water enters this back layer and none

passes through it. Any such unevaporated water drop-

60 lets collect along the contact area 22 and follow this

area to the bottom of the pad and then fall into the sump.

No separation material between the two pad parts is

necessary. The differences in the nature of the material

provide sufficient separation.

65 It is intended that substitutions for the exact materials

specified shall be within the ambit of the invention, and

that the arrangement of parts may be varied within the

scope of the disclosure.

I claim:

1. A composite evaporating pad for evaporative air coolers composed of an outer layer of wood excelsior and an inner layer of fibrous inorganic material treated with

a heavy non-hardening oil to render it water repellent and to entrap dust particles.

2. A pad for evaporative air coolers consisting of an outer layer of water absorbent fibrous wood material producing refrigeration by evaporation of water, and an inner filtering layer of non water absorbent inorganic material treated with heavy non-drying oil to render it water repellent.

3. A pad for evaporative air coolers consisting of a frame having side members, a louvered front plate, a back of coarse screen, and a water distribution trough at the top, a composite pad in said frame consisting of a front layer of water absorbent wood excelsior fitted against said louvered plate and a back layer of fibrous inorganic material, between said front layer and said screen, treated with heavy non-hardening oil rendering it water repellent and resistant to the passage of dust particles; said water distribution trough supplying water to said front layer of said pad only.

4. In an evaporative air cooler, having a case with a vertical outer wall provided with a rectangular opening for the reception of an evaporating pad, and having a water supply system including a pipe having a discharge

5 opening at the top of said rectangular opening, a composite evaporative pad composed of a rectangular frame removably fitting into said rectangular opening of said case including a water distribution trough perforated on the bottom at the top of said frame, an outer face consisting of a louvered plate, and a coarse screen closing its inner face, a composite evaporative pad having an outer portion of excelsior positioned adjacent said louvered plate and inner portion composed of inorganic wool-like fibers coated with non-hardening oil held between said excelsior pad and said coarse screen; said excelsior pad being disposed so that its top edge is below the perforations in the bottom of said water distribution trough.
